BRUNO SALZER AND GUSTAV WALTHER, OF CHEMNITZ, GERMANY.

STRAIGHT-KNITTING FRAME.

1,023,763.

Specification of Letters Patent.

Patented Apr. 16, 1912.

Application filed April 2, 1908. Serial No. 424,721.

To all whom it may concern:

Be it known that we, BRUNO SALZER and GUSTAV WALTHER, both subjects of the King of Saxony, and residents of Chemnitz, Saxony, Germany, have invented new and useful Improvements in Straight-Knitting Frames, of which the following is a specification.

This invention relates to straight bar knitting machines with jacquard apparatus for the production of regular openwork or lace goods.

A form of construction embodying the new invention is illustrated in the annexed drawings.

Figure 1 is a diagrammatic front-view of the apparatus as a whole. Fig. 2 is a plan-view of a detail. Fig. 3 is a side-elevation of a knitting frame provided with the mechanism shown in Fig. 1. Figs. 4, 5, and 6 are side elevations of three different parts of the mechanism shown in Fig. 1.

The jacquard apparatus comprises a rotatable card prism 1 carried by lever-arms 2 and adapted to be lifted and lowered by the said arms. A pattern-card 3 is intermittently moved by the prism and serves as in the known jacquard apparatus, for lifting the jacquard needles 4, as required by the pattern. The lower ends of the needles 4 are in the needle-plate 5 (Fig. 2) common to all the needles. Three hundred holes are bored in this plate for three hundred jacquard needles 4. Of these holes those numbered from 1 to 280 serve to receive the jacquard needles which form the pattern. The group of needles 1 to 20 on the left hand side of Fig. 2 is intended for those jacquard needles which form part of the mechanism which constitutes the present invention.

Figs. 1, 3, 4, 5, 6 only represent mechanism which is connected to, or co-acts with, the jacquard needles 1 to 20.

The machine to which my devices are applied is the well known cotton type straight fashioning knitting machine.

On the upper end surface of each jacquard needle 4 rests the shank of a lifting wire 6, so that each needle can be engaged by a lifting blade 7 of the lifting bar 8 and be pulled together with the wire 9 engaging the other end of the lifting wire. Let it, for example, be assumed that the jacquard needle 4' has dropped into a hole of the card 3. This causes the lifting wire 6' to drop

over the edge of the lifting blade 7. Since the lifting bar 8 is constantly oscillating in the directions indicated by the double-headed arrow 10, 11, it takes with it, during its next movement in the direction 10, the hook 6' together with the wire 9' and all parts connected with the same.

Of the wires marked 9 in Fig. 1 of which it will be assumed that there are twenty, each plays a certain definite part in the production of the fabric. Some examples of the co-action of the wires with the mechanism connected thereto will now be described. In order to produce a so-called slack course in the knitted web, the depth of lowering the loops must be increased. This is effected by means of the mechanism VI shown in Fig. 1 at the right hand end of the main shaft 21, and this mechanism is in part shown in Fig. 6, in side-elevation. The shaft 29 is the part by which the said depth is regulated. The device by which this is done is a well known part of said old machine and is therefore not illustrated in the drawing. All that is necessary to explain here is how the jacquard apparatus 3, 4, 6, 7, 9 automatically adjusts the mechanism VI (Figs. 1 and 6) to rock the shaft 29.

On the main or shogging shaft 21, Fig. 1, are arranged two cams 22 and 23 on the circumferences of which the rollers 24, 25 are to run. These two rollers are both mounted on the same axle, fixed to the lever 27. The roller 24 can be axially displaced on this axle by means of a forked lever 28. The latter is two-armed and pivoted to the lever 28; the lever 28 is rocked when the cord 12 fastened to it is pulled or released. The cord 12 passes over two guide-bars 13, 14, and is at 15 attached to the wire 9'. The spring 16 acts against the pull of the cord 12 and moves the lever 28 and roller 24 back to their initial positions when the cord 12 is released.

For the normal measure of making the loops, the lever 27 is moved by the roller 25 running on the cam 22. But if the jacquard needle 4' finds a hole in the card 3, the lever 6' is lowered upon the blade 7, and, at the next movement in the direction of the arrow-head 10, the lever 28 is rotated by means of the wire 9' and cord 12 and the roller 24 is moved on to the larger cam 23. In consequence of this the lever 27 oscillates through a larger angle, and moves with it

the shaft 29, to which it is rigidly fixed, and this motion of the shaft causes a slack course to be produced.

As a second example we will now explain 5 the mechanism marked V in Fig. 1; this mechanism is shown in Fig. 5 in side elevation. It serves for the formation of so-called ladders or open wales or dropped stitches. To the shaft 21 are rigidly fixed 10 three disks 30, 31, 32. Of these, the central one, 30, is circular and concentric with the shaft. The two others are eccentric, and their outlines, viewed in the direction of the axis, in part coincide with circumference 15 of the circular disk 30. Two rollers 33, 34 of equal size are pivoted on a pin rigidly fixed to a lever 35 which controls the operation of the old transfer or lace cover points for making drop-work. By means of a 20 forked lever 37 the roller 34 can be axially displaced on its axle. A spring keeps the rollers apart and also tensions a cord 36, which connects the forked lever 37 with one of the wires 9. At a certain stage of the 25 operation of the machine the cam-shaft 21 is, as is well known, axially displaced or shogged in the direction indicated by an arrow in Fig. 1. By this movement the cam 31 is brought into the plane of the roller 33. 30 While the roller 33 is on the circumference of the circular disk 30, the lever 35 is motionless, but when the said roller is on the cam 31, the lever 35 oscillates and imparts movement to the coverer points. If the 35 respective jacquard needle finds a hole in the card 3, the cord 36 is pulled and the forked lever 37 pushes the roller 34 on to the disk 32. The result is, that ladders are formed.

As a third example we will explain the 40 mechanism IV shown in Fig. 1 and Fig. 4. This mechanism serves to regulate the extent and direction of the lateral movements of the open or lace work mechanism. Wires 9 are connected by cords 67, 68, 69 with the 45 upper arm of a forked lever 65. The lower forked arm of the latter engages a disk 70. A spring 71 acts against the pull of the said cords 67, 68, 69. The disk is rotatable on a pin fixed to a lever 72, and is laterally movable. A small roller 74 running on a cam 50 73 lifts the lever 72 momentarily during each revolution in order that the roller 70 can be easily displaced. The cam 73 has five steps 73^a, 73^b, 73^c, 73^d, 73^e. On a pin 55 75 fixed to the lever 72 there is pivoted a tapering bar 66 the upper end of which rests, on the right hand side, against a fixed abutment 76, and has at the left hand side five steps 66^a, 66^b, 66^c, 66^d, 66^e. The height of 60 each of these steps is equal to one needle-division of the machine, so that a bar 77 leading to the open-work needle-bar can be moved step by step through distances exactly equal to the needle-divisions, by means 65 of the roller 76 when the bar 66 is raised or

lowered. In the position of rest of the open-work needle-bar the roller 70 is on the surface 66^a of the bar 66, therefore in the middle, and the roller 70 rolls on the surface 73^a. If during the covering the shaft 21 is 70 shifted in the direction indicated by the arrow, and the roller 70 remains stationary, the roller rolls on the surface 73^b of the cam, and the lever 72 is lowered accordingly and moves the bar 66 with it downward. 75 The roller 78 is then in contact with the surface 66^b and the needle bar is shifted toward the right by means of the bar 77. If the needle 4 corresponding to the cord 69 finds a hole in the card 3, the roller 70 is by displacement of the shaft 21 caused to roll on the surface 73^c of the eccentric and the bar 66 is so far lowered that the surface 66^c comes into contact with the roller 78; the cover-mechanism 77 is by this means pushed to the right to the extent of two needle-divisions. If instead of the cord 69 the cord 68 or 67 is pulled, the lever 65 is rotated through a larger angle, owing to the said cords 68, 67 being attached nearer to the fulcrum. The roller 70 is thus caused to roll on the surface 73^d or 73^e, and the roller 78 on the surface 66^d or 66^e.

As a fourth and last example we will explain the mechanism III shown in Figs. 1 95 and 3. This mechanism serves for axially displacing the cam-shaft 21 when the machine has been producing plain fabric, and the production of an open-work pattern is to commence, or narrowing is to take place. 100 This mechanism comprises a counter, by which the number of operations of the same kind which directly follow each other is regulated. The lever 49 (Figs. 1 and 3) acts in the usual manner to start the formation of the open-work pattern. The open-work always begins when the lever 49 is lowered to shog the shaft 21. In the drawing the lever 49 is shown held in its upper position by the lever 48. If the latter swings to the right, the lever 49 loses its support, it drops down, and the open-work begins. The lever 50 acts to start the narrowing by shogging the shaft 21 to a different extent from the lever 49. This operation begins when the lever 50 swings upward. In the drawing lever 50 is shown supported by the lever 47. When the lever 47 swings to the left, the lever 50 loses its support and swings upward. Then the narrowing begins. The lever 48 is moved by means of a rod 57, to which is fixed a pin 59 abutting against the lever 48. 110

A chain-wheel 40' is intermittently rotated by a pawl 40'' to move a chain 40 125 which is provided with studs 45. When a stud 45 passes under the hooked end of the lever 46 the latter is moved upward. In doing so it strikes against a projection of a lever 47', which is pivoted at 47'' and is 130

loaded at its free end by a weight. When the lever 47' is moved upward, its lower arm 47 moves toward the left and releases the above mentioned lever 50. Then the narr-
5 rowing commences. To the lever 47' is fixed a pin 55 in contact with the end of the lever 48'. When the pin 55 moves the lever 48 toward the right, as described above, the lever 48 at the same time moves the pin 55,
10 and the lever 47 is moved to the left and releases the lever 50. If therefore the bar 57 is moved toward the right until the pin 55 turns the lever 48 toward the right, not only the lever 49 is released, but also the lever 50. But, if on the other hand, a stud 45 lifts the lever 46, only the lever 50 is released and the lever 49 remains stationary. The ratchet-wheel 38 is intermittently rotated by the pawl 39. The said ratchet-
15 wheel 38 is rigidly fixed to a small pinion 58, which meshes with teeth of the bar 57. The latter is therefore moved step by step toward the right when the pawl 39 is operated. When the bar 57 has arrived at the
20 right-hand end of its travel the pin fixed thereto strikes the lever 48 and releases the lever 49.

The mechanism which will now be described serves to push back the bar 57 toward the left after it has arrived at the right end of its travel. The lever 58a is continuously oscillated on its stationary pivot 58'. It engages with its free end a pin 56' fixed to the bar 56, so that the latter is constantly reciprocated. With the two bars 56, 57 in the positions shown in Fig. 1 there is an open space between the left hand-end of the bar 56 and the right hand end of the bar 57, which is of the same length as
30 the travel of the bar 56. While the pin 60 prevents the pawl 39 from moving the ratchet wheel 38, the parts 57, 48, 49 remain at rest. And while the bar 56 is moved to and fro by the lever 58a, its left hand end comes each time lightly into contact with the right hand end of the bar 57. But when the pawl 39 has moved the wheel 38 and bar 57 to the extent of one tooth, the bar 57, on coming in contact with the bar 56 receives
40 a short backward thrust, which corresponds with a single tooth-space of the ratchet wheel 38. There are four distance-pieces 61, 62, 63, 64 which can be inserted singly or collectively between the two ends of the bars 56 and 57. Of these distance-pieces the smallest, 64, is only so thick, that if it alone is inserted between the two ends of the bars, the displacement of the bar 57 is only equal to one tooth-space of the wheel 38.
45 The part 63 is twice as thick, the part 62 four times as thick and the part 61 eight

times as thick. If therefore all four distance-pieces are placed between the two ends of the bars 56, 57, the bar 57 is displaced through a distance corresponding to 65 fifteen teeth. The parts 61, 62, 63, and 64 are suspended from levers 51, 52, 53, 54, connected by cords 41, 42, 43, 44, to wires 9, so that they are controlled by the jacquard apparatus 3, 4, 5, 6, 7. If all four distance 70 pieces have been placed between the ends of the two bars 56, 57 the pawl 39 must ascend and descend fifteen times before the pin 55 strikes against the lever 48 and releases the lever 49. Since the pawl 39 moves 75 up and down once for each row of stitches there will in this case be formed fifteen consecutive rows of plain stitches. During the production of these rows, *i. e.* during fifteen revolutions of the cam-shaft 21, the 80 jacquard apparatus 3, 4, 6, 7 is not required to work. Herein lies the great value and advantage of the invention.

Having described the nature of our said invention we declare that what we claim is:— 85

1. In a straight bar knitting machine, a group of needles, jacquard apparatus provided with means for controlling said group of needles for producing openwork patterns, a shogging shaft, means automatically adjusted by the jacquard apparatus for regulating the extent and direction of the lateral movements of said shogging shaft, and a counter controlled by said jacquard apparatus to regulate the number of consecutive 90 rows of plain stitches produced while the jacquard apparatus is out of action.

2. In a straight bar knitting machine, a group of needles, jacquard apparatus provided with means for controlling said group of needles for producing openwork patterns, a shogging shaft, means automatically adjusted by the jacquard apparatus for regulating the extent and direction of the lateral movements of said shogging shaft, a counter 100 controlled by said jacquard apparatus to regulate the number of consecutive rows of plain stitches produced while the jacquard apparatus is out of action, and means operatively connected with and actuated by 105 said shogging shaft for controlling a group of needles for producing slack courses and ladders.

Dated this nineteenth day of March, 1908.
In testimony whereof we affix our signatures. 115

BRUNO SALZER.
GUSTAV WALTHER.

In the presence of—

WILHELM F. KORYCKUY,
KARL YOPEL.
